(57) **CLAIM**

The ornamental design for a headset, substantially as shown and described.

DESCRIPTION

FIG. 1 is a perspective view of a headset as seen from the front, top and right sides;

FIG. 2 is a left side view thereof;

FIG. 3 is a front view thereof;

FIG. 4 is a right side view thereof;

FIG. 5 is a back view thereof;

FIG. 6 is a top view thereof; and,

FIG. 7 is a bottom view thereof.

The dotted lines depict environmental structure only and do not form any part of the claimed design.
